[57] CLAIM

The ornamental design for an exercise belt, as shown and described.

DESCRIPTION

FIG. 1 is a front perspective view of an exercise belt showing my new design;

FIG. 2 is a top plan view thereof in an unbelted condition and shown on a smaller scale;

FIG. 3 is a front elevational view thereof;

FIG. 4 is a rear elevational view thereof;

FIG. 5 is a bottom plan view thereof;

FIG. 6 is a left end elevational view thereof shown on a larger scale;

FIG. 7 is a right end elevational view thereof; and,

FIG. 8 is a cross-sectional view thereof taken along line 8—8 in FIG. 3.
